UNITED STATES PATENT OFFICE.

SIMON E. DAVIS, OF SAN FRANCISCO, CALIFORNIA, ASSIGNOR TO LEVI STRAUSS & CO., OF SAN FRANCISCO, CALIFORNIA, A CORPORATION OF CALIFORNIA.

DESIGN FOR CHILDREN'S ONE-PIECE OUTER GARMENT.

51,674.

Specification for Design.

Patented Jan. 8, 1918.

Application filed October 26, 1915. Serial No. 58,081. Term of patent 14 years.

To all whom it may concern:

Be it known that I, SIMON E. DAVIS, a citizen of the United States, residing in the city and county of San Francisco and State of California, have invented a new, original, and ornamental Design for Children's One-Piece Outer Garments, of which the following is a specification, reference being had to the accompanying drawings, forming part thereof.

Fig. 2 is a rear elevation of the garment.

I claim:

The ornamental design for a children's one piece outer garment, as shown.

SIMON E. DAVIS.

Witnesses:

JOHN H. HERRING,
NITA E. PENFIELD.
